CLAIM

The ornamental design for an eyeglass holder, as shown and described.

DESCRIPTION

FIG. 1 is a front, top and left side perspective view of an eyeglass holder showing our new design;

FIG. 2 is a top plan view thereof;

FIG. 3 is a bottom plan view thereof;

FIG. 4 is a right side elevational view thereof, the left side elevational view being a mirror image of the right side elevational view;

FIG. 5 is a front elevational view thereof;

FIG. 6 is a rear elevational view thereof; and,

FIG. 7 is a front and top perspective view of the eyeglass holder with a pair of eyeglasses held thereon.

The broken lines shown in the drawings are for illustrating environmental structures that form no part of the claimed design.
